UNITED STATES PATENT OFFICE

JAMES BURGESS DARGAVEL, OF ST. PAUL, MINNESOTA

DENTAL BRUSH

Application filed June 25, 1927. Serial No. 201,443.

My invention relates to brushes and particularly to brushes for use in conjunction with dental engines for cleaning drills, burrs, and similar instruments used in drilling and 5 filling teeth.

The principal object of my invention resides in providing a brush which may be quickly and conveniently removed from the dental engine and sterilized in boiling water, 10 or otherwise, so as to prevent the propagation or spreading of disease in the use of the same brush for cleaning the drills or burrs used on different patients.

An object of the invention resides in providing a mounting having a sleeve adapted 15 to screw upon the threaded hub of one of the pulleys of the dental engine, said sleeve having a stud-like projection issuing outwardly therefrom for the reception of one 20 of the brushes utilized in conjunction with my invention.

A still further object of the invention resides in constructing the brush used in my invention with an annulus of a suitable non- 25 corrosive heat resisting material adapted to be placed upon the stud-like portion of said mounting and to be driven thereby.

A feature of the invention resides in forming both said brush and mounting with teeth 30 adapted to intermesh upon the insertion of the brush thereon by means of which the brush may be rotated in conjunction with said mounting.

Another object of the invention resides in 35 providing both the brush and stud-like member with oppositely facing annular grooves along the contacting surfaces thereof and to dispose within said grooves an annular resilient retaining ring adapted to be compressed 40 to allow the removal of said brush and to be expanded to lodge within said grooves and hold said brush in fixed relation upon said stud-like portion of said mounting.

With the foregoing and other objects in 45 view, which will appear in the following description, the invention resides in the novel combination and arrangement of parts and in the details of construction hereinafter described and claimed.

In the drawings:

Fig. 1 is a longitudinal sectional view of one of the pulleys of a dental engine illustrating the application of my invention thereto and drawn to an enlarged scale.

Fig. 2 is a perspective view of the mounting used in conjunction with the pulleys shown in Fig. 1.

Fig. 3 is an elevational view of the obverse side of the brush used in conjunction with 60 the mounting shown in Fig. 2.

Fig. 4 is an elevational view of the reverse side of the brush shown in Fig. 3 with portions thereof cut away to illustrate the construction of the same.

Fig. 5 is a transverse sectional view of the mounting illustrated in Fig. 2 taken through the retaining ring groove thereof.

Fig. 6 is a view similar to Fig. 1 illustrating the application of the invention to another form of mounting.

In the usual practice of the profession of dentistry considerable lack of sanitation occurs in the cleaning of drills, burrs, and similar instruments utilized in the drilling and 75 filling of the teeth and other work in conjunction with the same. Such lack of sanitation results in the use of the same cleaning brush for cleaning the said drills and other instruments when the same are used on different patients. After using these instruments in the mouths of various patients and upon cleaning the same on the usual brush, deposits accumulate on the brush which are frequently transferred to drills or burrs when 80 used for other patients. The precaution for safety usually taken in the sterilizing of the drills and burrs is hence nullified by placing the same in contact with such brushes so that lack of sanitation exists with the result that 85 frequently the mouths of patients are contacted with germs of various diseases, such as pyorrhea, and other diseases as well as diseases affecting the body proper. My invention overcomes this disadvantage by pro-

90 viding a brush which may be rapidly and conveniently removed from its mounting upon the dental engine and which may be sterilized by steam or boiling water, or any of the other methods now in use for the purpose so 100

that the same degree of sanitation and precaution for the protection of the patients treated may be had at all times.

For the purpose of illustrating the use of my invention I have shown in Fig. 1 one of the pulleys A of a dental engine on which my improved brush may be readily applied. This pulley may be one of those over which the engine belt passes, though it can be readily comprehended that the brush may be attached to any rotating element of the device or may be driven from an independent source of motive energy, if desired. Pulley A consists of two halves 10 and 11 assembled upon a hub 12 and held in place thereon by means of two threaded nuts 13 and 14. The nut 14 is externally threaded at 15 to receive the mounting on which the brush proper is supported. It will become evident, however, that the type of pulley illustrated represents but a single type of pulley as now used on dental engines and that the invention can be attached to any form of dental engine now in common use.

The mounting on which the brush is attached is indicated in its entirety at B and comprises a sleeve 16 which is internally threaded at 17 to screw upon the threaded portion 15 of nut 14. This sleeve screws up against the portion 11 of pulley A so as to become firmly seated against the same and the threads 15 and 17 are cut in such a direction that the rotation of pulley A causes mounting B to become more firmly screwed upon the nut 14 as the device rotates. Extending outwardly from the sleeve 16 is formed a stud-like portion 18 which is of a smaller diameter than the sleeve 16 so as to provide a flange 19 connecting the same. This stud-like portion 18 may be constructed hollow as shown in Fig. 1 and closed by a suitable end wall 20, or the same may be constructed solid if desired.

The brush proper as best shown in Figs. 3 and 4 which is indicated in its entirety at C comprises an annulus 21 constructed of some suitable material, such as metal, ivory, porcelain, glass, or some similar substance. This annulus is arranged with a body portion 22 drilled with two rows of radial holes 24 and 25 disposed in staggered relation and arranged to receive bristles 26 forming the brushing element of the brush. The holes 24 and 25 extend to within a short distance of the inner periphery 27 of the annulus C and are connected by two annular grooves 28 and 29 which extend from said surface 27 inwardly into the body 22 and communicate with the said holes 24 and 25. In the construction of the brush, a wire indicated at 30 is successively looped up through each of the holes and the bristles placed within the loop. Upon drawing the wire taut the bristles are drawn into their respective holes and the wire caused to lie within the respective grooves 28 and 29.

In this manner the bristles are firmly held imbedded in the body portion 22 of the annulus 21 with the securing structure therefor issuing solely from the surface 27 of said annulus.

The brush C is adapted to be disposed upon the stud-like portion 18 of mounting B with the surface 21 thereof in contact with the outer periphery of said stud-like portion. When so disposed the grooves 28 and 29 with the wires 30 therein become concealed so that any drillings or other matter disposed upon the brush proper is prevented from entering or from leaving the said grooves and contacting with any of the instruments or the person of the patient treated. When the brush is constructed of metal, molten metal may be flowed into the grooves 28 and 29 which on hardening serves to enclose the same.

The brush C is driven from the mounting B by means of a plurality of teeth 31 formed on one of the faces 32 of the body portion 22, which teeth are adapted to intermesh with similar teeth 33 formed on the flange 19 connecting the stud-like portion 18 and the sleeve 16 of mounting B. By employing a large number of such teeth, practically no rotational adjustment is required to bring the brush into engaging position with the mounting so that a simple and effective device is provided for coupling the two members together. It is only necessary in applying the brush to the mounting to slip the same over the stud-like portion 18 and direct the same toward the teeth 33. Upon engaging said teeth a slight twist given to the brush will cause the respective teeth 31 of said brush to intermesh with the teeth 33 and bring the parts into the required engaging relation.

For holding the brush C in place upon the mounting B, the following construction is employed: In the stud-like portion 18 is cut an annular groove 34 which is adapted to receive a retaining ring 35. This retaining ring is constructed of resilient material and is normally of a diameter greater than the exterior diameter of the stud-like portion 18. Groove 34 is of a width sufficient to receive said retaining ring and is of a depth slightly greater than the diameter of said ring, so that the same may be compressed within said groove and completely concealed within the same to enable the annulus 21 to be slipped over the end of said stud-like portion. The end of the annulus 21 is formed with a neck 36 which is constructed with a groove 37 similar to the groove 34, said groove being arranged in oppositely facing relation, said grooves being adapted to register with one another when the brush C is mounted with the teeth 31 thereof intermeshing with the teeth 33 of said mounting. When so disposed, the retaining ring 35 is adapted to become lodged in the said groove 37 to occupy the position

shown in Fig. 1. It will be noted that the groove 37 is semi-circular in cross section and that the depth of the same is equal to one-half of the diameter of the said ring 35 so that when the parts are assembled as shown 5 in Fig. 1, the said ring is lodged partly in the groove 34 and partly in the groove 37, thereby holding the brush C in proper position upon the mounting B. For facilitating the 10 application of brush C to the mounting B the inner corners 38 of the teeth 31 are chamfered. When the brush C is centered relative to the stud-like portion 18 and directed towards the flange 19, the chamfered portions 15 31 engage the protruding portion of the retaining ring 35 and causes the said retaining ring to recede within the groove 34. This allows the body portion 22 of the annulus 21 to pass over the same and the teeth 31 of brush 20 C to intermesh with the teeth 33 of mounting B. As soon as the brush becomes so positioned the groove 37 falls opposite the groove 34, which allows the retaining ring 35 to spring outwardly into said groove 37 holding 25 the parts in locked position as previously stated.

To enable the rapid application or removal of the brush C without the grasping of the bristles thereon, I provide a flange 39 which 30 issues outwardly from the neck 36. This flange is arranged so that the same may be readily grasped by the fingers or finger nails so as to allow the brush to be applied or withdrawn from the mounting by a single movement. It hence becomes evident that it is merely necessary to either press the brush in place upon the mounting to attach the same thereto or it is merely necessary to pull upon the brush in a longitudinal direction to remove the same from the mounting.

In Fig. 6 I have shown the mounting B mounted upon a rotating element of the dental engine of a different type. In this case the mounting is attached to the shaft 40 of 45 the engine which is accomplished by means of reducing the size of the sleeve 16 to directly fit upon the shaft 40 as indicated at 41. To hold the said device from rotating, a set screw 42 is employed which is screwed 50 into a boss 43 formed on the said sleeve 41. It will become evident, however, that a suitable type of fastening device, may be used for securing the mounting B to any rotating element of the dental engine and that if 55 desired the said mounting and the pulley or other structure to which it is attached may be integrally cast or otherwise formed, as required.

With my improved invention, the brush 60 65 may be readily placed in the sterilizer and sterilized after each patient in the same manner, and together with the other instruments of the dentist. In this manner a highly sanitary and desirable construction is provided whereby the spreading or propagation of dis-

ease can be completely prevented in the use of dental apparatus. The device can be constructed at a nominal cost and if desired a number of brushes may be employed so that the dentist will have at all times a clean 70 brush in readiness for each new patient treated.

Changes in the specific form of my invention, as herein disclosed, may be made within the scope of what is claimed without departing from the spirit of my invention.

Having described my invention, what I claim as new and desire to protect by Letters Patent is:

1. In combination with the threaded hub 80 of a dental engine pulley, a brush mounting including a sleeve adapted to be screwed upon said hub, a stud-like member issuing outwardly from said sleeve, said stud-like member being of a diameter less than said sleeve to form a flange therebetween, an annular brush adapted to be mounted upon said stud-like member and to abut against said flange, means for retaining said brush upon said stud-like member, and interlocking 85 members formed on said flange and said brush for driving said brush through said mounting.

2. In combination with a rotatable member, a brush mounting secured thereto, said 95 brush mounting including a hub, an annular brush adapted to be slid axially along said hub for application thereto or for removal therefrom, means for releasing the hold of said brush upon said hub, a neck issuing 100 outwardly from said brush and a flange extending radially from said neck and in spaced relation to said brush proper, said flange being adapted to be grasped by the fingers for facilitating the removal of said brush from 105 said hub.

3. In combination with a rotatable member, a brush mounting secured thereto and including a hub, an annular brush removably fitted axially upon said hub, and a finger-piece on the brush to provide for convenience and sanitation in the handling of said brush, 110 said finger-piece being annular in form and arranged concentrically with respect to the axis of said mounting.

4. In combination with a rotatable member, a brush mounting secured thereto and including a hub, an annular brush removably fitted axially upon said hub, and a finger-piece protruding from one side of said brush to provide for convenience and sanitation in the handling thereof.

5. In combination with a rotatable member, a brush mounting secured thereto, said brush mounting including a hub, a flange extending outwardly from said hub, an annular brush adapted to be slid axially along said hub for application thereto or for removal therefrom, means for releasably holding said brush upon the hub, said brush having 125 130

a surface formed thereon facing a surface of said flange, and interlocking members formed on said surfaces for holding said brush from rotation.

- 5 6. In combination with a rotatable member, a brush mounting secured thereto, said brush mounting including a hub, an annular brush adapted to be slid axially along said hub for application thereto or for removal
10 therefrom, means for releasably holding said brush upon said hub and resisting the axial movement thereof, a finger piece formed on said brush, said hub having a portion extending through said brush in proximity to
15 said finger piece for cooperating with the finger in the removal of said brush from said mounting.

In testimony whereof I have affixed my signature to this specification.
